UNITED STATES PATENT OFFICE.

GEORGE ALBRECHT, OF PITTSBURG, PENNSYLVANIA.

CIGARETTE BOX AND CASE.

No. 889,568.

Specification of Letters Patent.

Patented June 2, 1908.

Application filed July 20, 1907. Serial No. 384,690.

To all whom it may concern:

Be it known that I, GEORGE ALBRECHT, a citizen of the United States of America, residing at Pittsburg, in the county of Allegheny and State of Pennsylvania, have invented certain new and useful Improvements in Cigarette Boxes and Cases, of which the following is a specification, reference being had therein to the accompanying drawing.

10 This invention relates to cigarette boxes and cases, and the invention has for its object to provide a cigarette box or case of an illusory nature to which considerable mystification is attached regarding the delivery 15 of the contents of the cigarette box or case.

My invention aims to provide a cigarette case or box for affording considerable amusement to persons favored with a cigarette, at the same time requiring dexterity on the part 20 of the owner of the cigarette case or box.

Briefly described my improved cigarette case or box consists of two movable compartments arranged within a suitable casing, one compartment being located within the other. 25 The innermost compartment is adapted to contain cigarettes, but by artfully manipulating the compartments, the cigarette holding compartment is first displaced, and then by illusively closing the case and manipulating the same, the other of said compartments can be withdrawn, thus perplexing one as to where the cigarettes have disappeared.

The detail construction entering into my 35 invention will be presently described, and then specifically pointed out in the appended claims.

In the drawings: Figure 1 is a perspective view of the cigarette case or box, illustrating 40 the compartments partially withdrawn, therefrom, Fig. 2 is a cross sectional view of the casing or box, Fig. 3 is a longitudinal sectional view of the same, Fig. 4 is a longitudinal sectional view of the casing with 45 both compartments withdrawn, and Fig. 5 is a similar view illustrating the outer or empty compartment withdrawn from the casing.

To put my invention into practice, I provide a casing 1 made of card board, leather or similar durable material. This casing can be readily used for advertisement purposes if so desired.

50 In the casing 1 is slidably mounted an outer or empty compartment 2, having an elongated opening 3 formed in its top. This

compartment is closed at its outer end and is provided with a tab or handle 4 to facilitate the withdrawal of the compartment from the casing 1, while at the inner end is 60 located a depending rim 5 for engaging a rib 6, carried by the casing 1, said rim and rib preventing the entire removal of the outer or empty compartment 2.

Slidably mounted in the outer or empty 65 compartment 2 is a cigarette holding compartment 7 conforming in shape to the compartment 2, with the exception that it is slightly smaller and is adapted to slide in said compartment. The rear end of the compartment 7 is provided with a piece of rubber or similar material 8 for frictionally engaging the bottom of the casing 1, while the top of the compartment 7 is cut away, as at 9, providing an opening conforming in size 70 to the opening 3 of the compartment 2.

In forming the openings 3 and 9 of the compartments 2 and 7 respectively, I allow sufficient material at each end of said compartments, whereby when the compartment 7 fits within the compartment 2, it will be impossible to detect at first glance the arrangement of the compartments, and to further deceive one as to the arrangement of the compartments, I make the compartments of 75 a similar material and a similar color.

The manner of practicing legerdemain with my cigarette case or box is as follows: Assuming that cigarettes have been placed in the inner compartment 7, the tab or handle 4 is pulled outwardly before displaying the cigarettes, as when offering a person one. After the manipulator of the cigarette case is positive that the cigarettes have been seen, the manipulator closes the case and by exerting a slight pressure upon the rear side of the casing 1; as indicated in Fig. 5, the inner compartment will be pressed downwardly causing the piece of rubber 8 to frictionally engage the bottom of the casing 1, and hold 80 the inner compartment, while the outer or empty compartment is withdrawn from the casing 1, thus mystifying the person to be favored with a cigarette, as to how the cigarettes have disappeared. It is obvious that 85 the majority of persons not aware that a trick is to be played, will unconsciously reach for the cigarette and consequently be fooled.

The cigarette case requires very little practice on the part of a person to artfully manipulate the same, and while I have herein 90 described the case or box as particularly de-

signed for cigarettes, it is obvious that it can be used for various articles.

Having fully described my invention, what I claim and desire to secure by Letters Patent, is:—

1. A cigarette box consisting of a flexible casing having a rib at the front end thereof an outer compartment slidably-mounted in said casing and having an elongated opening 10 formed in the top thereof, a depending rim carried by the rear end of said compartment for engaging said rib, a handle carried by the outer end of said compartment, a flexible cigarette holding compartment slidably-mounted within said outer compartment and having an opening corresponding in size to 15 and registering with the opening in said outer compartment, and a strip of resilient material carried by one end of said cigarette holding compartment in such position as to be capable of being pressed against the casing, substantially as and for the purpose described.
2. A flexible cigarette box embodying a 25 casing having a rib at the front end thereof, an outer compartment slidably-mounted therein and having an elongated-opening formed in the top thereof, a flexible cigarette holding compartment slidably arranged 30 within said outer compartment and having

an opening in its top corresponding in size to and registering with the opening in the top of said outer compartment, means carried by said cigarette holding compartment in such position as to be capable of being pressed 35 into frictional engagement with said casing, and means carried by said outer compartment for engagement with the rib of the casing to limit the outward movement of said outer compartment.

3. A box embodying a flexible casing, an outer compartment slidably mounted therein, a flexible inner compartment slidably arranged within said outer compartment, said compartments having registering openings 45 in the top thereof, means for limiting the outward movement of said outer compartment, and means carried by the inner compartment and located in such position as to be capable of being pressed into frictional engagement with said casing whereby the outer compartment may be withdrawn independently of the inner compartment.

In testimony whereof I affix my signature in the presence of two witnesses.

GEORGE ALBRECHT.
